[57] CLAIM

The ornamental design for a combined storage and table unit, as shown and described.

DESCRIPTION

FIG. 1 is a front elevational view of a combined storage and table unit showing our new design, the rear being identical thereto;

FIG. 2 is a top plan thereof; and

FIG. 3 is an end elevational view, the opposite end being identical thereto.

The bottom view is flat and unornamented.

Fig. 1
